UNITED STATES PATENT OFFICE.

ROBERT W. LUDEMANN, OF BUFFALO, MINNESOTA.

DOOR LATCH.

Application filed October 11, 1921. Serial No. 507,086.

To all whom it may concern:

Be it known that ROBERT W. LUDEMANN, a citizen of the United States, residing at Buffalo, in the county of Wright and State 5 of Minnesota, has invented certain new and useful Improvements in Door Latches, of which the following is a specification.

This invention relates to door latches generally, and particularly to latches for securing barn or granary doors.

The purpose and object of this invention is the provision of a pivoted or swinging latch which may be operated from either the inside or the outside of the door, but 15 which may be locked on the inside when necessary to prevent its unauthorized operation from the outside.

It is a further object of this invention to provide a locking device for the latch which 20 may be operated either from the inside or outside through the medium of a key in the possession of an authorized person.

It is a further object of the invention to provide a latch which is of sturdy construction and which may be easily applied to any type of door, and which is simple in construction and which may be manufactured at low cost.

Referring to the accompanying drawings 25 forming a part of this specification,—

Figure 1 is a front perspective view of a door with my latch applied thereto;

Figure 2 is a rear or inside view of the latch applied;

Figure 3 is a vertical sectional view on the line 3—3 of Figure 2;

Figure 4 is a view similar to Figure 3, but illustrating the locking device for the latch;

Figure 5 is a front elevation of the latch 40 applied to the outside of the door and showing the key for operating the locking device;

Figure 6 is a vertical sectional view on the line 6—6 of Figure 4, showing the latch locking device; and

Figure 7 is a perspective view of the key.

Referring now more specifically to the accompanying drawings by numerals of reference which indicate like parts throughout the several figures, a barn or other door is 50 designated by the numeral 2, this door being hinged to swing in the usual manner on vertical hinges, not shown, and cooperating with a door frame 4 of ordinary construction, except, as hereinafter designated as being modified for the specific purposes of its

adaptation to the present form of latch.

The door is provided upon the inside and outside adjacent its end with diametrically opposite face plates 6 and 8, being suitably secured as by screws 9.

Journalized in a transverse opening through the face plates 6 and 8 and through the door, is a latch spindle 10 having its ends extending beyond the face plates upon opposite sides of said door, the outer end having fixed 60 thereon an outside stop-bar 11 which may be swung during the movements of the spindle 10, through a portion of an arc of a circle as shown in Figure 1. This bar 11 normal abuts the vertical member of the door frame 70 4 and limits the inward movement of the door.

Secured to the outer threaded end of the spindle, through the medium of a nut 14 is an operating loop handle 16, so formed that 75 it may easily be grasped by the hand.

For the purpose of securing the door against outward movement on its hinges, I provide upon the inner end of the spindle 10, an inside latch bar 18, fixedly secured 80 thereto and which cooperates, when swung on the spindle to the position shown in full lines in Figure 2, with a latch plate 19 secured to the interior of the door frame. An inside operating arm or lever 20 rigidly secured to the lower portion of said latch bar 18 is for the purpose of swinging the same 85 either to latching position shown in full lines or to released position as shown in dotted lines in said Figure 2. It is of course 90 understood, that the stop bar 11 is never moved to a position wherein it will be free of said door frame 4 when the door is closed, and said bar 11 being rigid with the spindle upon which is also fixed the inside latch bar 95 18, it follows that it is limited in its upper swinging movement by the abutment of the lever 20 against the pull handle 40.

For the purpose of preventing unauthorized releasing of the latch from the outside 100 of the door, I provide a locking member 22 which is journalized in a transverse opening through said door and face plates, on the inner end of a stud 24, and to which it is rigidly secured, the outer end being provided with a rib 25 which cooperates with a slot 26 in the end of a key 28, which may be inserted in the keyhole 30 from the outside to swing the locking member into a position, 105 such that its toe 32 may be moved into a re- 110

cess 34 on the side of the said inside latch bar, and thereby prevent the latter being released.

Turning of the key in the proper direction removes the locking member from the recess 34 so that the latch may be swung to dotted line position in Figure 4.

It is of course understood that the latch may be released from the inside by merely raising the member 22 with the hand, whereupon the latch 18 may be operated by the arm or lever 20.

It will thus be observed that the door latch may be operated from either the inside or outside by a person having the proper key. A pull handle 40 is secured to the inside of the door so that the door may be swung from the inside.

It is also understood that various changes may be made in my invention without departing from the spirit thereof as defined by the following claims:

1. The combination with a door and a frame therefor, a spindle journaled in said door, a stop member carried by said spindle on the outside of said door, a latch member carried by said spindle on the inside of the door and means for oscillating said spindle to swing said latch member on the axis thereof and means for locking said spindle against movement.

2. The combination with a door and frame therefor having a latch plate, a spindle journaled for oscillating movement in said door, a stop bar carried by said spindle on the outside of said door and adapted for engagement with said frame to limit the inward movement of said door, a latch bar secured to said spindle on the inside of said door and cooperating with said latch plate on said frame; means for oscillating said spindle carried by the outer end of said spindle, means carried by said latch bar for oscillating the latter from the inside of the door and means for locking said latch bar when moved into latching position with respect to said latch plate.

3. In a latch for securing a door to a door frame, a spindle, a stop bar secured on one end thereof, a latch fixed to the other end thereof and provided with a recess in the side thereof, a locking member pivoted adja-

cent said latch bar, and means for swinging said locking member on its pivot to bring the toe thereof within said recess, whereby said latch bar is locked against pivotal movement.

4. The combination with a door and frame thereof having a latch plate, a spindle journaled in said door, a stop bar rigidly mounted on said spindle, exterior of said door, a handle also rigidly mounted on said spindle exterior of said door, a latch bar rigidly mounted on the inner end of said spindle on the inside of said door and adapted for movement into and out of engagement with said latch plate on the frame, said latch bar having a recess in the side thereof, a latch locking member pivotally mounted on the inside of said door adjacent said latch bar and having a portion for engaging in said recess, key operated means on said latch locking member whereby it may be oscillated by a key to engage or disengage it with said recess, and manually operated means for oscillating said latch bar from the inside or outside of said door.

5. The combination with a door and a frame therefor, a spindle journaled in said door, a stop member carried by said spindle on the outside of the door, a latch member carried by said spindle on the inside of the door and means for oscillating said spindle to swing said stop member and latch member on the axis of said spindle.

6. The combination with a door and a frame therefor having a latch plate, a spindle journaled for oscillating movement in said door, a stop member carried by said spindle on the outside of the door, and adapted to engage the door frame to limit the inward movement of said door, a latch bar secured to said spindle on the inside of said door and cooperating with said latch plate on said frame, a handle secured to said spindle on the outside of said door and an operating lever secured to said latch bar on the inside of the door, whereby said stop bar and latch bar may be operated simultaneously, from either the inside or outside of the door.

In testimony whereof I affix my signature.

ROBERT W. LUDEMANN.
